UNITED STATES PATENT OFFICE.

ALBERT M. KANTRO, OF CHICAGO, ILLINOIS.

DESIGN FOR AN ELECTRIC-LIGHT SHADE.

Application filed June 30, 1924. Serial No. 10,005. Term of patent 7 years.

To all whom it may concern:

Be it known that I, ALBERT M. KANTRO, a citizen of the United States, residing at Chicago, in the county of Cook and State of Illinois, have invented a new, original, and ornamental Design for Electric-Light Shade, of which the following is a specification, reference being had to the accompanying drawing, forming part thereof.

Figure 1 is a plan view, and
Figure 2 is a side elevation.

I claim:

The ornamental design for an electric light shade, as shown.

ALBERT M. KANTRO.
